FIG. 9.

Inventor:
Stefan Amzler

UNITED STATES PATENT OFFICE.

STEFAN AMZLER, OF OGDEN, UTAH, ASSIGNOR OF ONE-FOURTH TO WILLIAM C. SUMNER, OF OGDEN, UTAH.

CRUDE-OIL BURNER.

Application filed March 24, 1922. Serial No. 546,458.

To all whom it may concern:

Be it known that I, STEFAN AMZLER, a citizen of the United States, residing at 2042 Liberty Avenue, Ogden, in the county of 5 Weber, State of Utah, have invented a new and useful Improvement in Crude-Oil Burners, of which the following is a specification.

My invention relates to that class of 10 burner in use on railroad locomotives, sea-going boats, stationary power plants, or any power plant using the hydrocarbon type of burner.

Having observed through practical demonstration that most of the burners in use 15 are defective, in that these are made up of adjustable sections, and become warped and useless under strong heat, waste fuel, and cause delay and trouble, I have invented and 20 made improvements to overcome these defects by the construction of a crude oil burner, consisting of two members, each being a casting in one piece, and fastened together; each a part of the other, but independent of each other in function; and so 25 designed and constructed that it can be quickly installed on a railroad locomotive, and will fit the present standard arrangement of feed pipes and control valves without 30 any change in the majority of cases.

The top member and main body of the burner has no movable or adjustable parts, and therefore differs materially from many 35 of the burners now being made, in that it is cast in one piece having two compartments, an oil passage and a steam passage; these passages are again subdivided, so as to produce the result required and perform the 40 functions herein outlined.

The important features of this burner, and the construction thereof, will be shown 45 on the accompanying drawing, described and pointed out in detail in this specification by figures, letters and numerals, in which:

Fig. 1 is a side elevation showing the outlines of the burner, in upper and lower members, with internal features to be described hereafter.

Fig. 2 shows the top of the burner on a streamline plan, spreading uniformly out to the front, with a hood and vent holes to be described hereafter.

Fig. 3 is a vertical cross-section at the intake, showing location of feed pipes, hood 55 with vent holes, straps, clamps and hinge, with intake end of an air nozzle or blower.

Fig. 4 is a vertical and longitudinal cross-section through the main body of the burner, showing the internal construction 60 of both members, with channels, passages, shelves, projecting side walls, hood, feed pipes, outline top and bottom, to be particularly described hereafter.

Figs. 5, 6, 7, and 8 are horizontal cross-sections through the main body of the two members of the burner, showing the different divisions of Fig. 4 in separate views.

Fig. 9 is a vertical cross-section at the mouth or discharge end of the 70 two members, showing the relation of exits to each other and the relation of the upper member to the lower member—the air nozzle or blower.

Now, therefore, to more particularly define and describe this my invention, similar letters and numerals refer to similar parts throughout the several views, in which:

Fig. 4 is the principal view on the drawing, and is a vertical longitudinal cross-section through the middle, in which "a" is the top sloping downward from the hood "f" to the mouth of the burner, having vertical sidewalls "b", "b", connecting top "a" with bottom "c", provided with a fuel 85 oil passage "1" supplied by a feed pipe "2", capped by a hood "f" to make room for feed pipe and making one of the buffer shoulders "e", "e", (Figures 1, 2 and 4) provided with vents "a", "a", (Figures 1, 2 and 4) to allow 90 air to escape from the oil passage "3" which is divided by a vertical wedge-shaped partition "3", (Figures 4 and 5) between the middle horizontal partition 95 4, and the top "a", separating the oil passage from the steam passage "5", which is again divided by a horizontal partition "6" and a vertical partition "7" (Figures 4 and 6) supplied by a feed pipe "8", discharging at an upward angle "9", intercepting the oil flow "10" over a vaporizing shelf "11", and reinforced by a second atomizing steam jet "12", discharging at an upward angle on a vaporizing shelf "13" which is provided with a groove directly beneath 100 shelf "11" and between the walls "b", "b", 105

(Fig. 4) intercepting the oil that may escape the upper jets so that no waste can take place.

The upper member of the burner here pointed out is held in place by a strap or clevis "14", (Figures 1, 2 and 3 to which the second member, an air nozzle or blower "15" is attached with bolts "16", strap "17", nuts "18", clamp "19", on both sides of the burner; and further secured to the main body by hinge "20", screws "21" supplied and operated by compressed air from feed pipe "22", discharging through channel "23" over shelf "26" at the mouth of air nozzle or blower, held in place by shoulder "25" (Figures 1 and 3), adjusted by block "27" on perforated flat rod "28" held in place by keys "29" (Figures 1 and 9).

Figure 2 shows the application of the clevis "14" with bolts "32", by which the two members are combined and fastened to the fire box and ready for operation.

The object of this construction has been stated, and old principles applied in a new way is what is here described.

The main features will be pointed out with reference to Fig. 4, on the accompanying drawing, which is a vertical and horizontal cross-section through the center thereof.

By inspection it will be seen that the top "a" of the burner is sloping downward to the mouth, and that the upper part is cast in one piece, widening out uniformly to the front, right and left, provided with two passages, one for fuel oil and one for steam under pressure. The upper passage "1" (Fig. 4) is the oil channel and is in two compartments, divided by a vertical wedge-shaped partition "3" (Figures 4 and 5) of which the head is at the exit "10" and tapering back to a little within the feed pipe "2", each compartment provided with buffer shoulders "e" "e", top and bottom, to control the flow, in case of sudden stops or jars, and prevent spitting and loss of fuel, which is one of the present defects. I have also provided a hood "f" to make room for the feed pipes "2", to make a stop against the flange of the fire box, and provided this hood with vent holes "a" "a" (Fig. 2) for the release of air that may accumulate in the oil passages and check the flow. Each channel is provided with a downward slope in the floor "4" (Fig. 5) from the middle partition to the outer walls "b" "b", so that with a light feed the oil will settle to each side and produce even flame and heat in the fire-box; the two channels discharging over a rounded lip "10" (Figures 4, 5 and 6) where combustion takes place, allowing no part of the fuel oil to escape into the ash pan.

I have found by practical experience that thermic efficiency depends on the manner in

which the fuel and flame is directed into the fire box, and have reason to believe that dividing the liquid fuel into two branches, right and left, with a space between, admits more air, produces better results, and material saving of fuel.

To obtain this result, I have provided triple steam atomizing jets by dividing the steam channel "3" (Fig. 4) by a wedge-shaped horizontal partition "6" (Figures 4 and 6) of which the head makes the shelf "11" between the projecting walls "b" "b", tapering back to a little within the supply pipe "8" (Figures 4 and 6) so as to have a greater volume of steam above than below this partition. The upper part of this channel is again divided by a vertical triangular partition "7" (Figures 4 and 6) to produce a double steam jet, one directly under each of the exits of the oil channel, intercepting the flow by the steam jets and the vaporizing shelf "11," (Figures 4, 5 and 6), and this is again reinforced by the lower steam jet "12" (Figures 4 and 9) and the shelf "13", leaving a space or air passage between the steam jets to supply the oxygen required for combustion.

With this device and construction, I save a material percentage of fuel, and overcome the present waste of oil that is lost by spilling into the ash pan, which together with the carbon residue and sand forms a slag that absorbs heat and must be removed by hand at considerable cost.

To overcome this last difficulty I have provided a second member, an air nozzle or blower, operated by compressed air for three or four seconds at a time, when sand is introduced into the ash pan, to be removed by the forced draft, to clean the flues of the boiler.

This nozzle or blower has the outline and flaring shape of the main body and set at an angle so that the blast will keep the sand and carbon residue in motion long enough to be carried off by the draft and keep the ash pan free from slag.

Now, therefore, having described and pointed out the construction and operation of this burner, applying old principles in a new way, simply and practically, I desire Letters Patent of the United States for the protection thereof, and I claim:

1. A crude oil burner, consisting of a member cast in one piece, rectangular in cross-section, with sidewalls at right angles to the floor, diverging right and left from head to delivery, provided with a hood and converging top, from the vertical shoulder of the hood to a point where the sidewalls are beveled downward and meet with the projecting floor, having a passage for liquid fuel and a passage for steam under pressure, each passage provided with a nipple to connect with supply pipe, said passages sepa-

rated from each other by a main horizontal transverse partition, and again subdivided by horizontal and vertical partitions, provided with passages and exit openings, projecting shelves, sidewalls and floor.

- 5 2. A crude oil burner, including an air nozzle cast in one piece, rectangular in cross-section, having diverging walls from feed end to delivery, having a passage for
10 compressed air, an exit opening between projecting sidewalls and over a projecting floor, a nipple to connect to feed pipe from a main supply reservoir, provided with lugs, resting in clamping straps on each side, a
15 hinge by which this member is fastened to the burner nozzle under the floor thereof, a perforated rod and sliding block, the whole bolted to clevis in which burner nozzle rests.
20 3. A crude oil burner, having an oil passage supplied by a feed pipe, a hood over this feed pipe and over a buffer chamber, in which the inner converging shoulder forms the top, and the converging shoulder
25 of a horizontal and transverse partition extending from wall to wall forms the bottom of the buffer chamber and the floor of the oil passage, converging into a throat in said oil passage, which said oil passage is again
30 divided into two independent passages by an irregular vertical wedge-shaped partition, the point of the wedge a trifle within the feed pipe diverging to a head at the exit, directly under the converging top of
35 the main body and over a rounded lip formed by the principal partition, each passage rectangular in cross-section, diverging from throat to exit, having double exit openings, at least equal in area to the area
40 of the feed pipe.

4. A crude oil burner, having a double oil passage in the same plane, supplied by

the same feed pipe, each passage provided with a buffer chamber, capped by a hood having vent holes for each chamber, said 45 chambers converging into a throat for each passage, rectangular in cross-section, diverging with the walls of the burner, and a wedge-shaped partition between the passages, and a rounded lip extending beyond 50 the exit openings; the outside walls projecting beyond these exit openings, a rounded lip and beveled down to the projecting floor; in which the vertical wedge-shaped partition is the inside wall for each passage and the vertical outside walls of the main body are the outside walls of said oil 55 passages.

5. A crude oil burner, having an oil chamber provided with two exits above a 60 main horizontal and transverse partition, a steam chamber formed between said partition and the floor of the main body of the burner, provided with a nipple to connect with supply pipe from a main supply reservoir, divided into upper and lower passages by a horizontal and transverse wedge-shaped partition, the point of this wedge a trifle within and a little below the center of said feed pipe, terminating at the head 65 70 of the wedge in a transverse projecting corrugated shelf, the upper passage being subdivided by a triangular vertical partition, converging into thin apertures and exits, under the oil exits, and a rounded lip, and 75 in line therewith, over a transverse corrugated shelf and the projecting main floor, between and enclosed by projecting sidewalls.

In testimony whereof, I have signed my 80 name to this amended specification at Ogden, State of Utah, this 20th day of March, 1923.

STEFAN AMZLER.
